UNITED STATES PATENT OFFICE.

KENNETH P. BEATTIE, OF HOPKINS, MICHIGAN, ASSIGNOR TO THE TAYLOR, SMITH & TAYLOR COMPANY, OF CHESTER, WEST VIRGINIA, A CORPORATION OF WEST VIRGINIA.

DESIGN FOR A TEAPOT.

Application filed December 27, 1927. Serial No. 24,657. Term of patent 3½ years.

To all whom it may concern:

Be it known that I, KENNETH P. BEATTIE, a citizen of the United States, and residing at Hopkins, in the county of Allegan and State of Michigan, have invented a new, original, and ornamental Design for a Teapot, of which the following is a specification, reference being had to the accompanying drawing, forming a part thereof, in which—

I claim:

The ornamental design for a teapot, substantially as shown.

KENNETH P. BEATTIE.
